UNITED STATES PATENT OFFICE.

CLARK E. WYMAN, OF ST. PAUL, MINNESOTA, ASSIGNOR TO GRIGGS,
COOPER & CO., OF SAME PLACE.

DESIGN FOR A GROCER'S CABINET.

SPECIFICATION forming part of Design No. 28,498, dated April 19, 1898.

Application filed December 6, 1897. Serial No. 660,980. Term of patent 14 years.

To all whom it may concern:

Be it known that I, CLARK E. WYMAN, a citizen of the United States, and a resident of St. Paul, in the county of Ramsey and State of Minnesota, have invented and produced a new and original Design for Grocers' Cabinets, of which the following is a specification, reference being had to the accompanying drawing, forming a part thereof.

The drawing is a perspective view showing my new design for grocers' cabinets.

As shown in the drawing, the leading or material feature of my design consists in the upright cabinet, of rectangular section, hav-

ing a steep slanting top extending entirely 15 across the cabinet and at its edges flush with the sides of the cabinet and divided centrally into an upper and lower panel.

Having thus described my invention, the following is what I claim as new therein and 20 desire to secure by Letters Patent:

The design for a grocer's cabinet, substantially as herein shown and described.

C. E. WYMAN.
